B. BURGESS

FRUIT GATHERER

Filed April 11, 1923

UNITED STATES PATENT OFFICE.

BENJAMIN BURGESS, OF DANVILLE, ILLINOIS.

FRUIT GATHERER.

Application filed April 11, 1923. Serial No. 631,429.

To all whom it may concern:

Be it known that I, BENJAMIN BURGESS, a citizen of the United States, residing at Danville, in the county of Vermilion and 5 State of Illinois, have invented certain new and useful Improvements in Fruit Gatherers, of which the following is a specification, reference being had to the accompanying drawings.

10 This invention relates to certain improvements in fruit gatherers and it is an object of the invention to provide a novel and improved device of this general character wherein fruit or the like irrespective of its 15 size may be collected.

It is also an object of the invention to provide a novel and improved device of this general character wherein the fruit may be picked by either a push or a pull and gathered without injury.

20 The invention consists in the details of construction and in the combination and arrangement of the several parts of my improved fruit gatherer whereby certain important advantages are attained and the device rendered simpler, less expensive and otherwise more convenient and advantageous for use, as will be hereinafter more fully set forth.

30 The novel features of my invention will hereinafter be definitely claimed.

In order that my invention may be the better understood, I will now proceed to describe the same with reference to the accompanying drawings, wherein:—

Figure 1 is a view in elevation of a fruit gatherer constructed in accordance with an embodiment of my invention, the chute being shown in fragment;

40 Figure 2 is a vertical sectional view taken through the device as illustrated in Figure 1, the chute being omitted and a handle being applied;

Figure 3 is a sectional view taken substantially on the line 3—3 of Figure 1;

45 Figure 4 is a fragmentary sectional view taken at one side of the front opening of the hood.

As herein disclosed, my improved gatherer 50 comprises a hood consisting of a lower sleeve 1 of requisite diameter and which has its lower end or marginal portion defined by an outstanding bead 2. Soldered or otherwise secured to the upper portion of the 55 sleeve 1 is a reticulated fabric or wire mesh 3 constituting the side wall of the hood. This

fabric 3 extends almost entirely around the sleeve 1 and is flared upwardly and outwardly. The end marginal portion of the fabric or mesh 3 is engaged and clamped between the overlying laminations *a* of a binding strip 4 preferably of metal. The lower end portion of each of the strips 4 straddles a wall of the sleeve 1 from above as indicated at 5 in Figure 2, said overlying portions being soldered or otherwise secured to the wall of the sleeve 1. The upper end portions of the strips 4 and the upper marginal portion of the mesh or fabric 3 are soldered or otherwise secured to a depending flange 6 60 associated with the top member 7. The top member 7 is disposed on a predetermined downward incline toward the front opening afforded by the members 4. The lower portion of the member 7 is provided at its transverse center with a slot 8 substantially V-shaped in form and having the edges defining the slot rounded, said edges being defined by an upstanding flange 9.

Bridging the space between the lower portions of the members 4 and soldered or otherwise secured thereto is a plate 10, the lower portion of said plate overlying and soldered or otherwise secured to the adjacent portion of the sleeve 1. The upper marginal portion of the plate 10 is also provided with a substantially V-shaped slot 11, the edges defining the same being also rounded. Secured to the sleeve 1 is a barrel 12 into which is adapted to be fitted an end portion of an 90 elongated rod or pole 14 by which the device in its entirety is adapted to be manipulated.

The sleeve 1 is adapted to deliver within a chute C preferably netting the major portion of the chute, as illustrated in Figure 1, 95 being normally contracted or restricted but readily permitting fruit or the like to pass therethrough. This is of particular advantage as the travel of the fruit or the like through the chute is retarded whereby is 100 substantially eliminated the liability of injury as by bruising or the like.

The chute C is connected by the loops 15 with a band 16. This band 16 encircles the lower portion of the sleeve 1 directly above 105 and substantially in contact with the bead 2. One end portion of the band 16 is provided with a loop 17 through which the opposite end portion of the band 16 is threaded whereby said band may be properly fitted upon the sleeve 1. This band 16 is preferably of 110 metal which may be bended to effect the de-

sired securement of the band upon the sleeve 1.

In practice, fruit or the like may be readily picked by engaging the stem of the 6 fruit or the like within the slot 11 so that upon a slight upward movement being imparted to the sleeve 1 the fruit will be severed and fall through the sleeve 1 into the chute C. If preferred the stem of the fruit or the 10 like may be engaged within the slot 8 so that upon proper manipulation of the handle 14 the stem will be severed.

From the foregoing description it is thought to be obvious that a fruit gatherer 15 constructed in accordance with my invention is particularly well adapted for use by reason of the convenience and facility with which it may be assembled and operated, and it will also be obvious that my invention is 20 susceptible of some change and modification without departing from the principles and spirit thereof and for this reason I do not wish to be understood as limiting myself to the precise arrangement and formation of 25 the several parts herein shown in carrying out my invention in practice except as hereinafter claimed.

I claim—

1. A fruit gatherer comprising a hood 30 consisting of a bottom sleeve, a perforated wall extending a material distance around the sleeve, an end portion of the wall being secured to the sleeve, strips connected to the end marginal portions of said wall, a top 35 member secured to the upper portions of the wall and the strips, said top member at a point between the strips being provided with a slot, and a plate connected to and bridging the space between the lower portions of the 40 strips, said plate being provided with a slot.

2. A fruit gatherer comprising a hood consisting of a bottom sleeve, a perforated wall extending a material distance around the sleeve, an end portion of the wall being secured to the sleeve, strips connected to the end marginal portions of said wall, a top member secured to the upper portions of the wall and the strips, said top member at a point between the strips being provided with a slot, and a plate connected to and bridging the space between the lower portions of the strips, said plate being provided with a slot, each of said slots being substantially 50 V-shaped.

3. A fruit gatherer comprising a hood consisting of a bottom sleeve, a perforated wall

extending a material distance around the sleeve, an end portion of the wall being secured to the sleeve, strips connected to the end marginal portions of said wall, a top 60 member secured to the upper portions of the wall and the strips, said top member at a point between the strips being provided with a slot, a plate connected to and bridging the space between the lower portions of the 65 strips, said plate being provided with a slot, and an operating member engaged with the sleeve.

4. A fruit gatherer comprising a hood consisting of a bottom sleeve, a perforated wall 70 extending a material distance around the sleeve, an end portion of the wall being secured to the sleeve, strips connected to the end marginal portions of said wall, a top member secured to the upper portions of the 75 wall and the strips, said top member at a point between the strips being provided with a slot, and a plate connected to and bridging the space between the lower portions of the strips, said plate being provided with a slot, 80 said side wall being outwardly flared with respect to the sleeve.

5. A fruit gatherer comprising a hood consisting of a bottom sleeve, a perforated wall 85 extending a material distance around the sleeve, an end portion of the wall being secured to the sleeve, strips connected to the end marginal portions of said wall, a top member secured to the upper portions of the 90 wall and the strips, said top member at a point between the strips being provided with a slot, a plate connected to and bridging the space between the lower portions of the strips, said plate being provided with a slot, 95 and a chute engaged with the sleeve.

6. A fruit gatherer comprising a hood consisting of a bottom sleeve, a perforated wall extending a material distance around the sleeve, an end portion of the wall being secured to the sleeve, strips connected to the 100 end marginal portions of said wall, a top member secured to the upper portions of the wall and the strips, said top member at a point between the strips being provided with a slot, and a plate connected to and bridging the space between the lower portions of the strips, said plate being provided with a slot, 105 said side wall constituting a reticulated fabric.

In testimony whereof I hereunto affix my 110 signature.

BENJAMIN BURGESS.
